UNITED STATES PATENT OFFICE.

OSCAR MOBERG, OF NEW BRITAIN, CONNECTICUT.

DESIGN FOR A DISPLAY-STAND.

42,525.

Specification for Design.

Patented May 14, 1912.

Application filed January 29, 1912. Serial No. 674,220. Term of patent 7 years.

To all whom it may concern:

Be it known that I, OSCAR MOBERG, a citizen of the United States, and a resident of New Britain, in the county of Hartford, State of Connecticut, have invented a new, original, and ornamental Design for a Display-Stand, of which the following is a specification, reference being had to the accompanying drawing, forming part thereof.

The figure is a perspective view of a display stand embodying my invention.

I claim—

The ornamental design for a display stand as shown.

OSCAR MOBERG.
